ABSTRACT OF THE DISCLOSURE

Oral compositions, such as toothpaste, mouthwash, and the like, containing certain perfluoro-1,2-diphosphono-cycloalk-1,2-enes and salts thereof, which retard dental calculus formation without damaging tooth structure.

BACKGROUND OF THE INVENTION

The field of this invention is "oral compositions" which term is used herein to designate products which are not intentionally ingested in the ordinary course of usage but are retained in the oral cavity for a time sufficient to contact substantially all of the dental surfaces. Such products include for example dentifrices, mouthwashes, topical solutions, and prophylaxis pastes.

Dental calculus, or tartar as it is sometimes called, is a deposit which forms on the surfaces of the teeth at the gingival margin. Supragingival calculus appears principally in the areas near the orifices of the salivary ducts; e.g., on the lingual surfaces of the lower anterior teeth and on the buccal surfaces of the upper first and second molars, and on the distal surfaces of the posterior molars.

Mature calculus consists of an inorganic portion which is largely calcium phosphate arranged in a hydroxylapatite crystal lattice structure similar to bone, enamel and dentine. An organic portion is also present and may consist of desquamated epithelial cells, leukocytes, salivary sediment, food debris and various types of microorganisms.

As the mature calculus develops, it becomes visibly white or yellowish in color unless stained or discolored by some extraneous agency. In addition to being unsightly and undesirable from an aesthetic standpoint, the mature calculus deposits are constant sources of irritation of the gingiva and thereby are a contributing factor to gingivitis and other diseases of the supporting structures of the teeth, the irritation caused by deposits of calculus decreasing the resistance of tissues to endogenous and exogenous organisms.

A wide variety of chemical and biological agents have been suggested in the art to retard calculus formation or to remove calculus after it is formed. Mechanical removal of this material periodically by the dentist is, of course, routine dental office procedure.

The chemical approach to calculus inhibition generally involves chelation of calcium ion which prevents the calculus from forming and/or breaks down mature calculus by removing calcium. A number of chelating agents have been employed for this purpose. See, for example, British Pat. 490,384, granted Feb. 15, 1937, which discloses oral compositions containing ethylenediaminetetraacetic acid, and related polycarboxylic acids as anticalculus agents; German Auslegeschrift 1,149,138, published May 22, 1963, which discloses certain water-soluble diglycolates as anticalculus agents; and U.S. Pat. 1,516,206 which discloses oral compositions containing various sugar lactones for this purpose.

Although certain of the art-disclosed chelators are purportedly safe for use on dental enamel, the chemical similarity of calculus to the tooth structure limits the usefulness of the chelation approach since the more effective chelators can seriously damage the tooth structure by de-

2

calcification. Thus, the development of oral compositions which effectively retard calculus by calcium chelation has been impeded by safety considerations. Safe and effective anticalculus agents have been developed (see for example 5 U.S. application Ser. No. 668,702, filed Sept. 18, 1967, by Homer W. McCune and Nathaniel B. Tucker), now abandoned, however, researchers continue to seek alternative anticalculus agents for use in oral compositions.

SUMMARY OF THE INVENTION

10 It has now been discovered that certain perfluoro-1,2-diphosphonocycloalk-1,2-enes and salts thereof (sometimes referred to collectively hereinafter as "PFDC") possess the surprising capacity to retard the development of dental calculus without removing calcium from dental enamel or otherwise damaging the tooth structure when employed in oral compositions maintained within defined pH limits.

15 Although PFDC possess only nominal calcium sequestering capacities in the pH range characteristic of oral compositions, they effectively retard calculus formation by a mechanism that is believed to involve the inhibition of hydroxylapatite crystal growth as will be discussed more fully hereinafter.

20 Unlike inorganic polyphosphates such as pyrophosphates, the PFDC resist hydrolysis in aqueous products and therefore remain in an active form throughout the normal shelf-life of such products.

25 It is therefore an object of this invention to provide 30 novel oral compositions which retard the formation of calculus without otherwise affecting the tooth structure.

It is another object of this invention to provide an improve method for retarding the development of dental calculus.

35 Other objects will become apparent from the following detailed description.

DETAILED DESCRIPTION OF THE INVENTION

This invention is an oral composition effective in inhibiting the formation of dental calculus without adversely affecting the tooth structure comprising from about 0.01% to about 10% by weight of at least one anticalculus agent selected from the group consisting of those of the structural formula:

wherein n is an integer from 2 to 4 and M is hydrogen or a pharmaceutically acceptable salt forming cation such as alkali metal (e.g., sodium and potassium), alkaline earth metal (e.g., calcium and magnesium), stannous, indium, ammonium, or low molecular weight substituted ammonium e.g., mono-, di-, and triethanol-ammonium); the pH of the composition being within the range from about 5.0 to about 11.0.

50 PFDC can be prepared by any suitable method, however, an especially preferred method involves reacting trialkyl phosphites with 1,2-dichloroperfluorocycloalkenes in accordance with the procedures fully described by 55 Frank in J. Org. Chem., 30, 3663 (1965), and hydrolyzing the resulting esters.

The concentration of PFDC in the oral compositions of this invention can range from about 0.01% to about 10% by weight. Oral compositions which in the ordinary course of usage are likely to be accidentally ingested in substantial volumes should contain lower concentrations of PFDC. Thus, a mouthwash in accordance with this invention preferably contains less than about 3% by weight of PFDC. Dentifrice compositions and topical solutions, the latter to be administered professionally, can contain up to about 10% by weight, preferably from about 0.1% to about 5.0% by weight of PFDC.

The pH of the compositions of this invention can range from about 5.0 to about 11. Below about pH 5.0 damage to the dental enamel can occur in spite of the relative safety of the PFDC. Above about pH 11.0 difficulty is encountered in formulating products having satisfactory flavor, mildness, and safety. A preferred pH range is from about 6.5 to about 10. The pH of the composition, of course, is determinative of the predominant salt form of the PFDC present therein.

While it is not intended that this invention be limited by a particular theory of operation, it has been observed that PFDC interfere with the progress of calculus formation by interfering with the conversion of amorphous calcium phosphate to crystalline calcium hydroxylapatite. Amounts of PFDC which are much too small to chelate any appreciable quantities of calcium have been found to retard the formation of calcium hydroxylapatite. This selective action on the formative calculus deposits without demineralizing action on the dental enamel is surprising.

The efficacy of the compositions of this invention in calculus prophylaxis was demonstrated by the Crystal Growth Inhibition test which was conducted as follows:

CRYSTAL GROWTH INHIBITION DETERMINATION

As hereinbefore stated, the PFDC inhibit the growth of calcium hydroxylapatite crystals and in this way interfere with the normal formation of calcium hydroxylapatite from solution. This test is to determine the effect of PFDC on the calcium phosphate formed on addition of calcium ion to orthophosphate ion at constant pH. The procedure is as follows using a representative PFDC compound as an example:

1 ml. of a 0.1 M stock solution of $\text{NaH}_2\text{PO}_4 \cdot \text{H}_2\text{O}$ is diluted with 22 ml. of distilled water, 1 ml. of an aqueous solution of disodium 3,4,5-hexafluoro-1,2-diphosphonocyclopent-1,2-ene (HFDC) at a concentration sufficient to provide the desired ultimate concentration in the reaction mixture is added to the diluted NaH_2PO_4 solution and the solution is adjusted to pH 7.4 with sodium hydroxide. To this solution is added 1 ml. of a 0.1 M solution of $\text{CaCl}_2 \cdot 2\text{H}_2\text{O}$ preadjusted to pH 7.4 with sodium hydroxide. This mixture is held at a constant pH 7.4 throughout the reaction period.

After a sufficient reaction time as determined by the operator, generally within 90 minutes, the solution is filtered through a 0.45μ millipore filter pad, dried, and analyzed by X-ray diffraction. The solid calcium phosphate precipitated from the above-described solution without HFDC gives a typical hydroxylapatite pattern, while the calcium phosphate precipitated under the same conditions but in the presence of small amounts of HFDC of this invention is amorphous to X-rays.

Those compounds which are effective in inhibiting the growth of hydroxylapatite crystals at concentrations of less than 1.5×10^{-3} M under the conditions of this test are effective in reducing calculus formation in rats, while several compounds outside the scope of this invention that have little or no effect in this test do not reduce calculus in rats.

The concentration of HFDC required to inhibit the formation of calcium hydroxylapatite under the conditions specified above was found to be 1.82×10^{-4} M. The presence of this concentration of a representative PFDC in the test solutions of the Crystal Inhibition Test results in the precipitation of an amorphous calcium phosphate rather than crystalline calcium hydroxylapatite as occurs without HFDC. By way of comparison, ethylenediaminetetraacetic acid and nitrilotriacetic acid which have been suggested for use as anticalculus agents in the art fail to inhibit crystal growth of hydroxylapatite at molar concentrations of 2.45×10^{-3} and 2.54×10^{-3} , respectively. At higher concentrations, these prior art compounds prevent precipitation of calcium phosphate in this test because of their removal of calcium ion from solution by their se-

questering properties, not by their crystal inhibition properties.

The safety of PFDC for use in contact with dental surfaces is determined by the Continuous Immersion Test conducted as follows: Mature human teeth are immersed in aqueous solutions or dispersions of oral compositions containing PFDC in accordance with this invention at pH 7.0 and pH 10.0. Every four hours the teeth are examined for decalcification. Under visible light, enamel decalcification can be detected by a loss of luster, while opaque spots or slight surface roughening. The teeth are examined macroscopically and microscopically at the end of seven days. If no decalcification is observed through this period, the compositions cause no damage to dental enamel, and are considered safe in this respect for use in the oral cavity.

A dentifrice, especially toothpaste, containing PFDC is a preferred embodiment of this invention. Toothpaste compositions conventionally contain abrasive materials, sudsing agents, binders, humectants, flavoring and sweetening agents.

The abrasive materials and other adjuncts used in the practice of this invention are preferably not sources of much soluble calcium so that the crystal growth inhibiting capacity of PFDC is not depleted to an extent that its anticalculus activity is impaired. Thus, conventional abrasives such as dicalcium orthophosphate and calcium carbonate are preferably not used. However, predominantly β -phase calcium pyrophosphate prepared for example in accordance with the teachings of Schweizer, U.S. Pat. 3,112,247, granted Nov. 26, 1963, while contains relatively little soluble calcium can be used. An especially preferred class of abrasives for use herein are the particulate thermosetting polymerized resins as described by Cooley et al. in U.S. Pat. 3,070,510, granted Dec. 25, 1962. Suitable resins include, for example, melamines, phenolics, ureas, melamine-ureas, melamine-formaldehydes, urea-formaldehyde, melamine-urea-formaldehydes, cross-linked epoxides, and cross-linked polyesters.

Other suitable abrasives include alumina and the insoluble non-calcium metaphosphates such as sodium metaphosphate. Mixtures of abrasives can also be used. In any case, the total amount of abrasive in the dentifrice embodiments of this invention can range from 0.5% to 95% by weight of the dentifrice. Preferably, toothpastes contain from 20% to 60% by weight of abrasive. Abrasive particle size preferably ranges from 2μ to 20μ .

Suitable sudsing agents are those which are reasonably stable and form suds throughout a wide pH range, preferably nonsoap anionic organic synthetic detergents. Examples of such agents are water-soluble salts of alkyl sulfate having from 10 to 18 carbon atoms in the alkyl radical, such as sodium lauryl sulfate; water-soluble salts of sulfonated monoglycerides of fatty acids having from 10 to 18 carbon atoms, such as sodium monoglyceride sulfonates; salts of $\text{C}_{10}-\text{C}_{18}$ fatty acid amides of taurine, such as sodium N-methyl-N-palmitoyl tauride; salts of $\text{C}_{10}-\text{C}_{18}$ fatty acid esters of isethionic acid; and substantially saturated aliphatic acyl amides of saturated monoaminocarboxylic acids having 2 to 6 carbon atoms and in which the acyl radical contains 12 to 16 carbon atoms, such as sodium N-lauroyl sarcoside. Mixtures of two or more sudsing agents can be used.

The sudsing agent can be present in the dentifrice compositions of this invention in an amount from 0.5% to 5% by weight of the total compositions.

In preparing toothpastes, it is necessary to add some thickening material to provide a desirable consistency. Preferred thickening agents are hydroxyethylcellulose and water-soluble salts of cellulose ethers such as sodium carboxymethylcellulose and sodium carboxymethylhydroxyethylcellulose. Natural gums such as gum karaya, gum arabic, and gum tragacanth can also be used. Colloidal magnesium aluminum silicate or finely divided silica can be used as part of the thickening agent

to further improve texture. Thickening agents in an amount from 0.5% to 5.0% by weight of the total composition can be used.

It is also desirable to include some humectant material in a toothpaste to keep it from hardening. Suitable humectants include glycerine, sorbitol, and other edible polyhydric alcohols. The humectant can comprise up to about 3% by weight of the toothpaste composition.

Suitable flavoring agents include oil of wintergreen, oil of peppermint, oil of spearmint, oil of sassafras, and oil of clove. Sweetening agents which can be used include saccharin, dextrose, levulose and sodium cyclamate.

Several representative oral compositions illustrating this invention are set forth in the following examples.

EXAMPLE 1

A toothpaste of the following composition is prepared by conventional methods.

Parts by weight	
Water	31.58
Sorbitol	6.25
Saccharin	0.12
Calcium pyrophosphate ¹	39.00
Glycerine	18.00
Sodium alkyl (coconut) sulfate	0.40
Sodium coconut monoglyceride sulfonate	0.75
Sodium carboxymethyl cellulose	1.15
Mangesium aluminum silicates	0.40
Flavoring	0.85
Disodium salt of 3,4,5-hexafluoro-1,2-diphosphono-cyclopent-1,2-ene	1.50
pH	5.90

¹ Prepared in accordance with U.S. Pat. 3,112,247 granted Nov. 26, 1963.

This composition effectively retards calculus formation on dental enamel and when tested in the Continuous Immersion Test described herein no decalcification is noted after seven days exposure. ,

Toothpaste composition substantially identical to the composition of Example I are prepared with the dipotassium salt of 3,4 - tetrafluoro-1,2-diphosphonocyclobut-1,2-ene, the monocalcium salt of 3,4,5,6 - octafluoro-1,2-diphosphonocyclohex-1,2-ene; 3,4 - tetrafluoro-1,2-diphosphonocyclobut-1,2-ene; 3,4,5,6 - octafluoro - 1,2-diphosphonocyclohex-1,2-ene; and the di(triethanolammonium) salt of 3,4,5-hexafluoro-1,2-diphosphonocyclopent-1,2-ene rather than the disodium salt of 3,4,5-hexafluoro-1,2-diphosphonocyclopent - 1,2-ene, adjusting the pH to 5.9. These compositions substantially retard calculus formation and do not decalcify dental enamel.

Further examples of toothpaste compositions in accordance with the invention are set forth in Table 1 below.

Several mouthwash compositions are prepared in accordance with this invention as follows:

		Parts by weight			
5	Example	X	XI	XII	XIII
Component:					
	Glycerine	10.0	10.0	10.0	10.0
	Ethyl alcohol	16.5	16.5	16.5	16.5
	Tween 80	.12	.12	.12	.12
10	Saccharin	.045	.045	.045	.045
	Sodium cyclamate	.075	.075	.075	.075
	Flavor	.088	.088	.088	.088
	PFDC	2 1.0	3 3.0	4 5.0	6 7.0
	Water	Balance			
	pH 6	6.0	8.5	10.0	10.0

¹ Polyoxyethylene (20 moles of ethylene oxide) sorbitan monooleate—a nonionic emulsifier supplied by Atlas Powder Company.

² 3,4,5-hexafluoro-1,2-diphosphonocyclopent-1,2-ene.
³ Triammonium salt of 3,4,5-hexafluoro-1,2-diphosphonocyclopent-1,2-ene.

⁴ Tripotassium salt of 3,4,5-hexafluoro-1,2-diphosphonocyclopent-1,2-ene.

⁵ Trisodium salt of 3,4,5-hexafluoro-1,2-diphosphonocyclopent-1,2-ene.
⁶ Adjusted to value indicated with the base solution corresponding to the salt used.

When used in the same manner as conventional mouthwashes, the salt used:

When used in the same manner as conventional mouth-wash, at least once daily, each of the above compositions materially reduces accumulation of calculus on the surfaces of teeth. No decalcification is observed after seven days exposure of dental enamel to these compositions.

EXAMPLE XIV

A prophylaxis paste for use by the dentist for removal of stains and polishing the teeth after mechanical removal of calculus deposits is formulated as follows:

		Parts by wt.
	Navajo pumice	77.10
	TiO ₂	4.00
	Glycerine	17.75
35	Hydroxyethylcellulose	.22
	Saccharin	.33
	Disodium salt of 3,4,5-hexafluoro-1,2-diphosphono-cyclopent-1,2-ene	4.0
40	Trisodium salt of 3,4,5-hexafluoro-1,2-diphosphocyclopent-1,2-ene	4.0
	pH	7.5

When applied to the teeth with a prophylactic rubber cup in the conventional manner, this composition helps retard the development of new calculus deposits.

Toothpowders and the like can be prepared by conventional methods and containing, in addition to the usual ingredients, an amount of PFDC within the ranges specified herein, to provide an effective means of retarding calculus formation without damaging the tooth structure.

Those components other than PFDC which were included in the foregoing examples and various mixtures of

those components are illustrative of carriers suitable for use in the oral cavity.

In reference to pH adjustments in the foregoing examples, it is to be understood that a base of a cation corresponding to the salt form of the PFDC employed is used. In each case in which the PFDC was added in its acid form to the example compositions, the pH was adjusted to the specified value with NaOH. Adjustments in pH to more acid levels when adding the PFDC in the salt forms is accomplished with HCl. It will be obvious to those skilled in the art that pH adjustments can be made with any acid or base suitable for use in the oral cavity.

What is claimed is:

1. A method for inhibiting the formation of dental calculus without adversely affecting tooth structure, comprising the application to dental surfaces of a composition comprising from about 0.1% to about 5.0% by weight of an anticalculus agent selected from the group consisting of those of the formula:

wherein n is an integer from 2 to 4 and the pharmaceutically acceptable salts thereof, and a carrier suitable for use in the oral cavity, the pH of the composition being within the range from about 5.0 to about 11.0.

2. The method of claim 1 wherein the anticalculus agent is 3,4,5-hexafluoro-1,2-diphosphonocyclopent-1,2-ene or an alkali metal, alkaline earth metal, stannous, indium, ammonium, or low molecular weight substituted ammonium salt thereof.

3. In a dentifrice composition containing from about 5% to about 95% by weight of a dentifrice abrasive and having a pH within the range from about 5.0 to about 11.0, the improvement comprising the incorporation therein of from about 0.1% to about 5.0% by weight of an anti-

calculus agent selected from the group consisting of those of the formula:

wherein n is an integer from 2 to 4 and the pharmaceutically acceptable salts thereof.

4. The composition of claim 3 wherein the anticalculus agent is 3,4,5-hexafluoro-1,2-diphosphonocyclopent-1,2-ene or an alkali metal, alkaline earth metal, stannous, indium, ammonium, or low molecular weight substituted ammonium salt thereof.

5. In a mouthwash composition containing a flavoring agent and having a pH within the range from about 5.0 to about 11.0, the improvement comprising the incorporation therein of from about 0.1% to about 5.0% by weight of an anticalculus agent selected from the group consisting of those of the formula:

wherein n is an integer from 2 to 4 and the pharmaceutically acceptable salts thereof.

6. The composition of claim 5 wherein the anticalculus agent is 3,4,5-hexafluoro-1,2-diphosphonocyclopent-1,2-ene or an alkali metal, alkaline earth metal, stannous, indium, ammonium, or low molecular weight substituted ammonium salt thereof.
